UNITED STATES PATENT OFFICE.

THOMAS CLARENCE HEISEY, OF NEWARK, OHIO, ASSIGNOR TO A. H. HEISEY & CO., OF NEWARK, OHIO.

DESIGN FOR A GOBLET OR SIMILAR ARTICLE.

59,474.

Specification for Design.

Patented Oct. 25, 1921.

Application filed April 5, 1919. Serial No. 287,838. Term of patent 14 years.

To all whom it may concern:

Be it known that I, THOMAS C. HEISEY, a citizen of the United States, residing at Newark, Ohio, have invented a new, original, and ornamental Design for Goblets or Similar Articles, of which the following is a specification.

Figure 1 is a side elevation of a goblet having thereon the ornamental design of the invention.

Fig. 2 is a similar view of the same article but seen from another view point.

The ornamental surface design is not confined to the specific article illustrated, as it may be applied to other articles of glassware suited to receive the ornamentation.

I claim—

The ornamental design for a goblet or similar article substantially as shown and described.

T. CLARENCE HEISEY.
